UNITED STATES PATENT OFFICE

JOHN FREDERICK WAKE, OF DARLINGTON, ENGLAND

DRYING OF ROAD-MAKING AGGREGATES AND OTHER BROKEN OR GRANULAR MATERIALS

Application filed September 21, 1925, Serial No. 57,667, and in Great Britain September 23, 1924.

This invention relates to the drying of broken or granular materials in bulk, such as road-making aggregates, by a fluid drying medium or agent.

5 The invention is directed to that type of drying which is effected on, what is or may be termed, the counter-current principle, that is to say, of the kind wherein the material is, in the process of drying, compelled to 10 travel in a direction opposite to that followed by the drying medium or agent.

The object of the invention is to obtain 15 highly efficient drying simply and inexpensively; and to provide an apparatus or dryer free of moving mechanism apart from the customary adjuncts necessary to compose a complete plant, such as, for instance, the elevators which feed and discharge the material, and the fans for use in connection with the 20 furnaces to supply heated air to constitute the drying medium or agent.

To this end, I constrain the material to flow or move gravitationally and continuously in an independent stream or column or streams 25 or columns while subject to the drying medium or agent constrained to flow and circulate in the opposite direction, the stream or column or each of the streams or columns being of a symmetrical contour from end to end.

30 The stream-flow or columnar-movement of the mass of material is successively concentrated, disrupted and collapsed, or contracted and expanded, thereby producing a pulsation of the whole stream- or column-mass 35 promoting the continual exposure of fresh surfaces of the material to the drying medium or agent.

Plant or apparatus for effecting the drying as explained comprises a casing whereto 40 the material is fed; a plurality of open-ended tubes or pipes positioned within the casing through which the material passes under gravity, and provided with spaced openings throughout their length establishing communication with the casing; means for supplying a drying medium or agent to the casing whence it passes into the tubes or pipes; means for withdrawing the spent drying medium or agent and moisture from the casing 45 and the tubes or pipes; means for charging

the material to be dried into the casing and tubes or pipes; and means for discharging the dried material therefrom.

The tubes or pipes are each composed of intercommunicating parts adapted to admit 55 or compel the alternate contraction or expansion, or concentration, disruption and collapse, of the material passing therethrough as a stream or column as it is fed at one end of the tube or pipe and discharged at the other 60 end while the drying medium or agent is introduced into the tube or pipe at the latter end and discharged at the opposite end.

I will now describe, by way of example, 65 one way of, or apparatus for, carrying my invention into practice particularly applicable for drying broken stone for making tarred macadam for roads which I have illustrated more or less diagrammatically in the accompanying drawings whereto I will refer 70 as occasion requires, premising that of the several figures:

Fig. 1 is a central vertical sectional elevation of the apparatus constructed in accordance with the invention; and 75

Fig. 2 is a horizontal section thereof on the line X—X; while

Figs. 3, 4 and 5 are elevations of various modifications of the intercommunicating members, represented in the last two figures, 80 composing a tube or pipe.

The same numerals of reference are adopted throughout to designate the same or corresponding parts.

According to this example, I construct a 85 cylinder to constitute a casing 10 which I set vertically upon an appropriate support or foundation 11. Within, and transversely of, the casing 10 I fix a plurality of plates 14—14 in spaced relation constituting partitions 90 forming a series of compartments 15—15 within the casing 10, communication between these various compartments being suitably effected. These plates or partitions 14—14, further, function to carry the components 95 of a plurality—six, for instance,—of cylindrical sectionally-constructed vertically-arranged tubes or pipes 12—12 for the passage of the material to be dried, which is fed into the upper ends of the tubes or pipes from a 100

common supply chamber or hopper 23, and is discharged at the lower end into a common delivery chute 29 provided with an outlet 33, the flow of the material throughout being accomplished wholly by gravity.

Accordingly, each partition plate 14 has six equidistant holes near its periphery for the components or sections 34—34 of the tubes or pipes 12—12 for which it acts as a tube-plate, while the top plate 14 and the bottom plate 14, are, in addition, provided with a central hole 35, the hole 35 in the top plate 14 being for the discharge of the spent drying medium or agent and the products of the drying, and the hole 35 in the other plate 14 being for the inlet of the drying medium or agent.

Each tube or pipe component or section 34 consists of a funnel-shaped member or tube, that is to say, it comprises a cone-shaped portion 36 merging into, and terminating in, a cylindrical portion 37 of reduced diameter, the over-all length of the member 34 approximating the distance between two adjacent partition plates 14, 14, and the lengths of the conical and cylindrical portions 36 and 37 being substantially the same. The upper end of the conical portion 36 of each member 34 is secured to the partition plate 14, while the complementary cylindrical or depending portion 37 depends with its end almost to (see Figure 1) or slightly projecting into the conical end 36 of the next subjacent member 34 (see Figure 3), with the exception of the lowermost which communicates with the delivery chute 29. The cylindrical or depending portion 37 of each member 34 is peripherally gapped, the gaps 38—38 taking the form of spaced slots extending from the extreme end for a distance towards the conical portion 36, and being of such dimensions as to permit of the passage of the material. Thus these gaps or slots 38—38 constitute both outlets for the discharge of the material and inlets for the supply of the drying medium or agent. Therefore, the assemblage of members 34—34 composes a complete tube or pipe 12 constraining the material, as well as the drying medium or agent, to follow a sinuous and interrupted course in passing through it.

The feed or supply chamber 23 for the material is formed as a continuation of the upper end of the casing 10, and it consists of a truncated-cone part whose base is constituted by the uppermost partition plate 14, and of a reverse conical part whereinto the material is delivered through the agency of a shoot and an elevator.

The delivery chute 29 is likewise constituted as a continuation of the bottom end of the casing 10, and it, also, consists of an inclined wall part 28, a vertical wall part 30 and an upper wall formed by a plate 39 secured to the casing 10. The plate 39 is a

counterpart of the lowermost partition plate 14 of the casing 10, and it is at a distance therefrom equal to the spacing of the partition plates 14—14, consequently the lowermost components, sections or members 34—34 of the various tubes or pipes 12—12 project closely to, or slightly into, the corresponding holes in the plate, while, too, a compartment 40 obtains whereinto the drying medium or agent is initially and directly introduced.

The outlet 44 through the plate 39, which communicates with a subjacent chute 29, is controlled by means comprising a disc 41 revolvably fitted thereover so as to also constitute a part of the upper wall of the chute 29. The disc 41 is provided with a plurality of peripheral openings 42—42, less in number than that of the sectional tubes or pipes 12—12—three, for instance. The disc 41 is mounted on a shaft 43 constituted, in the example, supported centrally of the chute 29 in any suitable manner, and a worm shaft 45 and a worm gear 46 are combined in appropriate fashion for continuously or periodically rotating the disc 41.

A pipe 19 is secured to the upper partition plate 14 about the central hole 35 therein to constitute an outlet for the spent drying medium or agent and the products of the drying, and it may be designed to operate as an ordinary chimney, or it may be connected with a suction or other device for effecting a positive discharge. This outlet pipe 19 projects through the feed or supply chamber 23, and about its junction with the partition plate 14 a structure 27 of truncated-cone formation is positioned for the purpose of deflecting the material towards, or distributing it, to the uppermost funnels or conical portions 36—36 of the components, sections or members 34—34 of the various tubes or pipes 12—12, thereby promoting equality of the feed.

The drying medium or agent adopted is hot air supplied from or by a known or other appropriate source such as a furnace; and, as already explained, it is introduced into the lowermost compartment 40 of the casing 10, that is the extra or special one immediately above the delivery chute 29. The casing 10, in proximity to this compartment 40, is surrounded by a brick flue 20 connecting with the furnace or other source, and communication between the two is established by a plurality of ports 22—22 provided in the walls of the casing 10 and of the flue 20. Consequently, the hot air enters the compartment 40 whence some of it passes through the gaps or slots 38—38 of the components, sections or members 34—34 of the various tubes or pipes 12—12 therein into the next compartment 15 above, while some of it passes directly into such compartment 15 by way of the central hole 35 in the partition plate 14. Thus the hot air passes from the second compartment 15

15 to the superimposed compartments 15—15 in turn by way of the pipe components, sections or members 34—34, eventually entering the outlet pipe 19 for discharge as a spent medium or agent along with the products 5 arising from the drying.

If desired, the hot air may, also, be directly introduced into, and in the spent condition, along with the drying products, be withdrawn from, one or more of the superimposed compartments 15—15, which may be the same or not, that is to say, the hot air may be supplied to a compartment 15 other than that from which it may be withdrawn. This may be 10 accomplished by extending a part 47 or parts 15 of the main flue 20 up the casing 10 and providing interconnecting ports 48—48 at the required places, and by furnishing a spent air outlet pipe 49 or pipes having a branch 20 or branches 50—50 connecting with the designed compartment 15 or compartments 15—15, by way of suitable ports 51—51, the branch outlet pipe 49 or pipes being independent of, or allied with, and of the same 25 operative character as, the main outlet pipe 19. The flue extension 47 or extensions and the outlet pipe 49 or pipes may be situated without the casing 10. The various ports 48—48 and 51—51 for the active and spent 30 medium or agent are controlled by valves as indicated at 52—52, or otherwise, adapted to be actuated to effect any desired system or sequence of operation.

It will now be obvious that, when the plant 35 is in full work, the various sectional tubes or pipes 12—12 are fully charged with material, and likewise the delivery chute 29 and the feed or supply chamber 23, and that the material, as it approaches the bottom of the 40 tubes or pipes 12—12, becomes more dry and is subjected to the drying medium or agent when hottest. It will, further, be seen that the material, as it enters each cylindrical portion 37 of a pipe component, section or mem- 45 ber 34, concentrates or contracts to form a column which disrupts or expands through the gaps or slots 38—38 therein, and, when it reaches the funnel portion 36 of the next section 34, it further disrupts or bulges or 50 expands and collapses, and then is reassembled or concentrated or contracted as a column again in and by the cylindrical portion 37 of that funnel 36, when the same actions are successively or alternately repeated until 55 the material falls or discharges into the delivery chute 29, while simultaneously the hot air is split up and circulated through and around the concentrated, disrupted and collapsed material. Thus the material, when it 60 enters the delivery chute 29, by the rotation of the disc 41 is thoroughly and uniformly dry because the expanding, disrupting and collapsing actions function as a means of agitating and changing the position of the 65 pieces composing the bulk material, whereby

fresh surfaces are continually being exposed to the hot air, with the consequential advantageous drying effect.

It will be obvious that the formation of the components or sections 34—34 of the tubes or pipes 12—12 may be variously modified whilst retaining the pulsating action of the material in the course of its stream-flow or columnar-movement. Three examples of this are illustrated in Figs. 3, 4 and 5 to which I will refer in turn.

Fig. 3 represents each component or section fashioned as a continuous conical tubular member 34, the basal end 36^a of one cone being assembled relatively to the apexal end 37^a of the adjacent cone 34^a as shown, and in much the same way as the parts 36 and 37 already described with reference to, and as illustrated in, Fig. 1.

According to Fig. 4, the component or section 34^b is of compound structure whose constituents resemble the constituents 36 and 37 of the Fig. 1 construction, inasmuch as it comprises a conical tubular member 36^b and a reversely-conical deflector 37^b, the two being suitably connected together. Here, again, the components or sections 34^b—34^b are assembled so that the relation of the parts 37^b—37^b with reference to the parts 36^b—36^b is as explained with regard to the original 95 construction.

The construction illustrated in Fig. 5 is substantially the same as that just described, the difference being that the constituent or element 36^c is fashioned as a basin with an opening in its bottom wherewith the apex of the constituent or deflector 37^c is associated.

In each of these three modifications, the parts 36, 36^a, 36^b and 36^c are supported by the partitions 14 as in the original construction, and operates in conjunction with the complementary parts 37, 37^a, 37^b, 37^c as explained with reference to the parts 36 and 37 of the basic construction.

In addition to the modifications just explained, it will be manifest, without giving specific illustrations, that other constructional components may be variously altered in shape or arrangement without affecting the practical results explained, or affecting the scope of my invention. It may, however, be convenient to briefly exemplify some, hence I will do so.

What I claim and desire to secure by Letters Patent is:

1. For drying road-making aggregates and other broken or granular materials on the counter-current principle, apparatus comprising a casing; a plurality of open-ended perforated notched short tubes or pipes situated within the casing in vertical and horizontal spaced relation to each other and to the casing; transverse imperforate plates fixed at intervals within the casing 125 positioning the tubes or pipes, serving as a 130

means to control the direction of the circulation of air by preventing passage except by the notches, and partitioning the casing into compartments, wherethrough the tubes or pipes pass, means at the top of the casing for receiving the material to be dried and delivering it to the tubes or pipes; means at the bottom of the casing for receiving the material from the tubes or pipes and discharging it; means establishing communication between one or more of the casing-compartments and a source of supply of a drying medium or agent; and means establishing communication between the remaining compartment, or one or more of the remaining compartments, and an outlet or outlets for the spent drying medium or agent and the products of the drying operation.

2. For drying road-making aggregates and other broken or granular materials on the counter-current principle, apparatus comprising tubes or pipes composed of a plurality of intercommunicating funnel-like members or tubes having staggered openings such as perforations or slots, in parts, and assembled with their larger ends in juxtaposition to the smaller ends of the superjacent members or tubes and means whereby the material passes sinuously in one direction through said tubes and the drying agent passes in the other direction through said tubes.

3. For drying road-making aggregates and other broken or granular materials on the counter-current principle, apparatus comprising a casing; a plurality of short open-ended notched, funnel shaped or conical tubes or pipes situated within the casing in vertical and horizontal spaced relation; means at the top of the casing for receiving the material to be dried and delivering it to the tubes or pipes; means for supplying a drying medium or agent to the casing; means at the bottom of the casing for receiving the material unchecked from the tubes or pipes and discharging it; and means for controlling the outlet including a revolvably-mounted disc; means for revolving said disc, said disc having one or more discharge openings therein.

50 4. For drying road-making aggregates and other broken or granular materials on the counter-current principle, apparatus comprising a casing; a plurality of notched open-ended short tubes or pipes situated within the casing in vertical and horizontal spaced relation, and communicating with the casing through openings provided in their walls at intervals; means at the top of the casing receiving the material to be dried and delivering it to the tubes or pipes; means for supplying a drying medium or agent to the casing; means at the bottom of the casing receiving the material from the tubes or pipes and delivering it to an outlet; and means including a disc, having a discharge opening or

several such openings, rotatably supported below, and controlling, the outlet, devices operating the disc periodically or continuously, and a stationary cone-structure deflecting the material towards the discharge opening or openings of the disc.

In testimony whereof, I affix my signature.

JOHN FREDERICK WAKE.
